UNITED STATES PATENT OFFICE.

JOHN WILLISON, OF CLEVELAND, OHIO, ASSIGNOR, BY MESNE ASSIGNMENTS, TO NATIONAL MALLEABLE AND STEEL CASTINGS COMPANY, OF CLEVELAND, OHIO, A CORPORATION OF OHIO.

CAR COUPLER.

Application filed August 6, 1921. Serial No. 490,233.

Fig. 1 is a plan of a pair of couplers embodying my invention in interlocked or coupled position; Figs. 2 and 2^a are elevations of opposite sides of a single coupler; 5 Figs. 3 and 4 are plans of couplers angled to extreme positions to the left and right, respectively; Fig. 5 is a plan showing the couplers guided into partial buffing position; Fig. 6 is a plan showing the coupler in full 10 buffing position and also the operation of the uncoupling mechanism; Fig. 7 is a plan showing the operation of the uncoupling mechanism; and Fig. 8 shows a modified 15 form of uncoupling mechanism.

My invention relates to couplers of the vertical plane type, and comprises a coupler which interlocks with the opposing coupler head without employing any of the usual 20 movable parts such as knuckles or locks. My improved coupler is also provided with means for effecting the uncoupling of the interlocked heads. My invention further comprises the various features which I shall 25 hereinafter describe and claim.

Referring to the drawings, A and B indicate the opposing coupler heads, each of which has rigid jaws 2 and 3 and a connecting buffing face 4 inclined at an angle to the center line of the coupler. Each 30 coupler has a recess 5 to the rear of the jaw 2 to receive the complementary jaw 3 on the opposing coupler and permit their respective pulling faces 6 and 7 to become engaged. These pulling faces 6 and 7 are set at such 35 an angle to the center line of the coupler that when these faces are engaged and the couplers are under draft they will tend to swing toward each other. In buff, also, the inclination of the buffing faces 4 tends to 40 swing the couplers toward each other, but they are maintained in proper alignment by the faces 8 of the jaws 2 bearing against the faces 9 on the jaws 3.

As the couplers come together the vertical 45 faces 10 on the jaws 2 and the faces 4 will guide the jaws 3 into the recesses 5 in the rear of the jaws 2, and when draft is applied the pulling faces 6 on the jaws 2 will engage the corresponding faces 7 on the jaws 50 3, which form reentrant angles with the faces 8 on these jaws.

Each coupler is provided with an uncoupling member 11, which is mounted in a transversely extending slot 12 in the coupler

shank just back of the coupler head and is 55 prevented from removal therefrom by any suitable means, such as a pin and slot connection 13, by which the uncoupling member is permitted to be advanced into operative position or to be retracted into inoperative 60 position. The forward portion 14 of slot 12 is inclined downwardly to the rear so as to allow the member 11 to slide rearwardly into inoperative position after the uncoupling operation has been completed. 65

When the couplers in moving together buff in the extreme angled position shown in Fig. 3, the engagement of the ends of the buffing faces 4 on the jaws 3 causes these faces to slide to the right along each other through the position shown in Fig. 5 into the full buffing position shown in Fig. 6, with the jaws 3 in the recess 5 of the jaw 2. Then, when draft is applied, the face 7 of the jaw 3 pulls forward against the face 6 of the jaw 2 and the couplers are thus brought into 70 locked position shown in Fig. 1. When the couplers meet in the extreme angled position shown in Fig. 4 they are swung to the left until the jaws 2 clear the jaws 3 and then the buffing faces 4 guide the jaws 3 into the recesses 5, as has just been described above. 75

In uncoupling, the couplers are buffed to full buffed position, as shown in Fig. 6, and then either one of the uncoupling members 80 85 11 is swung over and pushed forward into the position in the recess 16 indicated by the dotted lines in Fig. 6. Then, when the couplers are under draft, the point of the jaw 2 will ride along the rear face of the uncoupling member 11 and be prevented from interlocking with the jaw 3, and the couplers will swing away from each other until the jaws 2 clear the jaws 3. The uncoupling member 11, as soon as it is relieved from the pressure from the point 15 of the jaw 2, 90 slides rearwardly down the incline 14 into the position shown in Figs. 3 and 4 and during subsequent coupling movements is pushed back out of the way by the jaw 2, 100 as is shown in the full line position of the uncoupling member in Figs. 6 and 7. 95

In Fig. 8 I have shown a modified form 105 of my invention in which the uncoupling member 11' is mounted in a slot in the jaw 2. In this form the member 11' in advanced position fills in the reentrant angle in the jaw formed by the surfaces 6 and 8, and thereby

prevents the face 7 of the jaw 3 from engaging the face 6 of the jaw 2.

My invention is of great advantage, since it dispenses with the use of the usual 5 knuckles and locks but nevertheless provides a light, strong and compact coupler of extreme simplicity which can be readily coupled or uncoupled. While no positive lock is provided, the couplers can not pull 10 apart unintentionally unless they are first buffed together to take up the contour slack, and then while pulling apart one or both must slide laterally against the friction of the carry iron. As this lateral motion of 15 the coupler is always opposed by friction of the carry iron, and as the couplers are normally forced laterally into full coupling position every time they are buffed, so that their pulling hooks are lined up to engage 20 under draft, it is impossible to conceive accidental parting of the couplers under normal service conditions.

The terms and expressions which I have employed are used as terms of description 25 and not of limitation, and I have no intention, in the use of such terms and expressions, of excluding any mechanical equivalents of the features shown and described, or portions thereof, but recognize that various 30 structural modifications are possible within the scope of the invention claimed.

What I claim is:

1. A coupler head of the vertical plane type having a plurality of jaws integral therewith, a cavity on the inner side of one of said jaws having reentrant angles arranged to receive a complementary jaw of a similarly formed coupler head, each of said first named jaws having acutely angled surfaces for interlocking with the complementary jaws on the opposing coupler head.

2. A coupler head of the vertical plane type having a plurality of jaws, one of said jaws being of hook shape and arranged to receive within the bight of the hook a jaw of a similarly formed coupler head, and the other of said jaws being formed to fit into the bight of a hook-shaped jaw on the opposing coupler head, the said jaws having acutely angled faces comprising means for interengaging and holding the coupler heads together.

3. A coupler head of the vertical plane type having a laterally extending buffing face, a plurality of pulling jaws arranged to receive and engage complementary jaws of an opposing coupler for effecting coupling, and an uncoupling mechanism comprising a member insertable into one of the said jaws 55 to prevent the complementary jaw on the opposing coupler from entering and interlocking therewith.

4. A coupler head of the vertical plane type having a plurality of jaws, one of said 60 jaws having a recess therein, a similarly

formed opposing coupler head having a jaw with a projection arranged to enter the recess in the first mentioned head for effecting a coupling, an uncoupling member in the first mentioned coupler head mounted to permit the said coupler member being moved into said recess to prevent entrance therein to of the said projection and thereby prevent coupling.

5. A coupler head of the vertical plane type having a plurality of pulling jaws and a buffing face therebetween, one of said jaws having a recess on its rear side arranged to receive a complementary jaw on a similarly formed coupler head for effecting a coupling, and an uncoupling member mounted in said coupler head and movable transversely thereof into said recess to prevent coupling.

6. A coupler head of the vertical plane type having a plurality of interlocking jaws, one jaw having a recess on its rear side and the other a projection on its forward side, buffing faces on each jaw and also a buffing face between the jaws, said buffing faces being arranged to engage complementary buffing faces on a similarly formed opposing coupler and move said jaws laterally into position to engage a complementary projection and a complementary recess on the opposing coupler.

7. A coupler head of the vertical plane type having a pair of jaws each having a pair of acutely angled pulling faces, a clearance space to the rear of each such pair of faces arranged to give room for complementary jaws on an opposing coupler head having similarly formed faces, and an inclined buffing face between said jaws comprising means for bringing the said acutely angled faces into position for engagement.

8. A coupler head of the vertical plane type having a laterally extending buffing face, a plurality of jaws having a pulling engagement with complementary jaws of an opposing coupler for effecting coupling, a guiding face upon the forward side of one of said jaws, the plane of said guiding face being in advance of the forwardmost portion of the other of said jaws.

9. A coupler head of the vertical plane type having a laterally extending buffing face, a plurality of pulling jaws arranged to receive and engage complementary jaws of an opposing coupler for effecting coupling, one of said jaws being located forwardly of the other, guiding faces on the forward side of each of said jaws, the guiding face of the forwardmost jaw being of greater lateral extent than the distance between said jaws for the purpose of bridging the space between the jaws of an opposing coupling and thereby guide said couplers into coupling position.

JOHN WILLISON.
